UNITED STATES PATENT OFFICE

ETTORE BUGATTI, OF PARIS, FRANCE.

INTERNAL-COMBUSTION ENGINE.

1,223,762.

Specification of Letters Patent. Patented Apr. 24, 1917

Application filed April 6, 1916. Serial No. 89,292.

To all whom it may concern:

Be it known that I, ETTORE BUGATTI, a subject of the King of Italy, residing in Paris, France, have invented certain new and useful Improvements in or Relating to Internal-Combustion Engines, of which the following is a specification.

The present invention relates to internal combustion engines of the kind wherein the valves are controlled by a cam shaft placed above the cylinders, an arrangement which presents many difficulties in execution, especially where there are a number of valves.

Hitherto it has been difficult to arrange an admission valve and an exhaust valve in one plane perpendicular to the cam shaft. If the valves be placed in two such planes spaced apart there is a loss of space.

The present invention consists in an improved construction which permits the placing of the admission and exhaust valves directly opposite one another, that is to say in one and the same plane which is perpendicular to the axis of the cam shaft and, moreover, the forming of groups comprising four valves disposed symmetrically with respect to two planes which are perpendicular to one another and pass through the axis of the cylinder.

The improved construction consists in arranging above the head of the engine cylinder superposed tappet members or levers and each provided with one or more openings to allow respectively the passage therethrough of a finger or equivalent member attached to the lower tappet and of the valve spindle or spindles controlled by the upper tappets; this system of control permits the use of separate cams for controlling the admission and exhaust valves.

The invention will be described with reference to the accompanying drawing in which:

Figure 1 is a vertical section, broken along the line $y-y$ of Fig. 2, through the head of an engine cylinder having the invention applied.

Fig. 2 is a plan of the same with a part plan of an adjacent cylinder.

From Fig. 2 it will be seen that an admission valve a and an exhaust valve b are disposed in each of the planes $x-x$, $y-y$, which are perpendicular to the axis of the cam shaft c on which are keyed the admission and exhaust cams d , e .

The valves b are controlled by means of

an upper tappet member or lever f having the form of a plate which is hinged at g and provided with a projection m . In tappet plate f is an opening h ; through this opening can move freely a projection i carried by the lower tappet j which is hinged at k and acts through its free end on the valves a . The lower tappet lever, also in the form of a plate has openings l through which can pass freely the ends of the rods of the valves b . Alternatively the tappet f can be provided with dependent projections adapted to traverse the openings l and act upon the ends of the spindles of valves b .

If the two projections m and i , which if desired may be furnished with rollers, be not situated in the same vertical plane, separate cams, that is to say, cams placed in different planes, can be employed for controlling the valves.

The operation of this system of control is as follows:—In turning, the shaft c acts by cam d on projection m carried by the tappet f and thereby causes the lowering of valves b , so that the exhaust ports become open. When the cam e acts in its turn on projection i on tappet j it causes the lowering of this latter which by its free end bears on the end of the spindles of valves a , the lowering of which brings about the opening of the admission ports.

The tappet members or levers may have any form; provided they have the opening or slots necessary for the reception of the projection of the lower tappet and the spindles of the valves b and have parts that are subject to the action of the cams.

Having now particularly described and ascertained the nature of my said invention and in what manner the same is to be performed, I declare that what I claim is:

1. An internal combustion engine having twin exhaust and admission valves located directly opposite one another in a plane perpendicular to the cam shaft, and having tapped levers controlling said valves respectively, the lever for one pair of valves located above the lever for the other valves, said levers having projections, and a cam shaft having cams acting on said projections respectively, such projection on the lower tappet lever passing up through the plane of the upper lever.

2. An internal combustion engine having exhaust and admission valves located di-

rectly opposite one another in a plane perpendicular to the cam shaft, and having superposed tappet levers controlling said valves respectively, the upper lever having an opening through which a cam projection on the lower lever passes, and the lower lever having an opening through which passes a connection from the upper lever to the spindle of the valve controlled thereby, 10 and a cam shaft having cams acting on said levers respectively.

3. An internal combustion engine having twin exhaust and admission valves for each cylinder placed opposite one another in 15 planes perpendicular to the cam shaft, combined with tappet levers one operating the twin exhaust valves and the other the twin

admission valves, said levers arranged in planes one above the other, the upper lever having an opening through which passes a cam projection on the lower lever, and the lower lever having openings through which pass connections from the upper lever to the spindles of the valves controlled thereby, and a cam shaft having cams acting on said levers respectively.

In witness whereof, I have hereunto signed my name in the presence of two subscribing witnesses.

ETTORE BUGATTI.
